UNITED STATES PATENT OFFICE.

EDWARD FRANCIS SHALLOW, OF PHILADELPHIA, PENNSYLVANIA.

GAGE-COCK.

979,344.

Specification of Letters Patent.

Patented Dec. 20, 1910.

Application filed October 18, 1910. Serial No. 587,771.

To all whom it may concern:

Be it known that I, EDWARD FRANCIS SHALLOW, a citizen of the United States, residing at Philadelphia, in the county of Philadelphia and State of Pennsylvania, have invented new and useful Improvements in Gage-Cocks, of which the following is a specification.

The present invention has reference to improvements in gage cocks, and more especially with relation to the testing valves ordinarily employed in connection with such devices, the improvements in question comprehending generally a special construction for valves of that type, and a particular form of controlling means for the same.

A structural embodiment of the invention is illustrated in the accompanying drawing, wherein—

Figure 1 is a perspective view of the improved gage cock. Fig. 2 is a longitudinal vertical sectional view. Fig. 3 is a plan view.

In said drawing, 1 designates the case of the cock, and 2 the threaded stem formed integral with the case and adapted to screw into the boiler head at the proper point.

Through the stem 2 and the adjacent arm 3 of the case is formed a longitudinal bore 4 which communicates by way of a channel 5 of reduced diameter with an internally threaded bore 6 alining with the first bore and formed through the opposite arm 7 of the case. Bore 6 also communicates, adjacent its inner end, with a second channel 8 that opens, in turn, into the valve seat 9 formed in the neck portion 10 of the case, which portion is provided with a spout 11 whose bore opens into said seat through a port 12 formed in the seat wall, as shown in dotted lines in Fig. 2.

Bore 6 is designed to receive the threaded stem of a rotatable valve 13 provided with an operating handle 14 of any suitable type. Said stem passes through an opening formed in a cap 15 threaded on arm 7, and its inner end is reduced, as indicated by the numeral 16, so as to enable it to fit seat 17 formed at the point of intersection between bore 6 and channel 5. The arrangement is such, therefore, that communication between the boiler and the channel 8 leading to the spout 11 may be opened or closed by turning the controlling valve 13 in the proper direction. This valve, however, is designed to remain

in open position under ordinary circumstances. The outer end of bore 6 may be suitably packed, as will be understood.

The bore which constitutes and produces seat 9 receives the stem of the main or testing valve 18. The outer portion of this stem is slightly enlarged, and is formed with steep spiral threads 19 which engage the corresponding threads formed in the inner wall of a collar 20 fitted on the upper end of the case neck 10 and held in place by means of a threaded cap 21. The top wall of said cap bears upon an out-turned flange 22 formed on said collar, the joint between the latter and the neck being rendered fluid-tight in any suitable manner. The lower end of the stem of valve 18 is normally held squarely against its seat 9, by devices hereinafter described, thus closing port 12 and cutting out communication between the supply channel 8 and the spout.

The retaining means for the testing valve preferably comprehend a torsion spring 23 bearing at one end against a depending stud 24 carried by the valve handle lever 25, and engaged at the other end with the upstanding end of a pin 26 which projects laterally from a lateral arm 27 formed integral with the body portion of the case. The coiled central portion of this spring embraces a vertical pin 28 formed upon arm 27. The handle lever above referred to is attached by means of a set-screw 29 or the like to the upper end of the valve stem 18, and is designed for connection to an operating device (not shown) of the usual or any preferred type, for which purpose its outer end is provided with an aperture 30.

In operation, the controlling valve 13 is maintained normally in open position, while the testing valve 18 is held in closed position by the torsion spring, thus opening communication between the boiler and the channel 8 through the medium of bores 4 and 6 and channel 5, but cutting out communication between said channel 8 and the port 12 leading to the spout. When it is desired to test the level of the water in the boiler, the handle lever is shifted into the position shown in dotted lines in Fig. 3, against the pressure of its controlling spring, whereupon valve 18 will be turned and will rise to an extent sufficient to uncover port 12, thereby enabling the water to flow out, if its level be high enough, through the port 110.

and spout, the failure of the water to appear evidencing the fact that it has fallen below the proper level, as will be understood. The quick upward movement of the 5 testing valve requisite to enable it to uncover port 12, when its handle lever is swung through a comparatively small arc, is effected by means of the steep threads 19 with which the valve stem is provided.

10 It will be observed that the controlling valve 13 is employed in addition to the testing valve, and that the controlling spring for the latter valve is located exteriorly of the case. By utilizing the controlling valve, 15 it is possible to entirely cut off communication between the boiler and the branch 8 leading to the valve seat 9, so as to permit said seat to be ground or otherwise renewed, without entailing the detachment of the 20 device from the boiler, and also to permit the testing valve itself to be withdrawn and inspected, and replaced if necessary. By locating the spring exteriorly of the case, it is enabled to exert its full pressure upon 25 the handle lever and, at the same time, is not exposed to the action of the water. The arrangement of the spring, moreover, is such that it is perfectly supported and held against displacement.

30 I claim as my invention:

1. In a gage cock, the combination, with a hollow case provided with an interiorly-located valve seat, and with an exteriorly-located arm formed with a lateral projection; of a valve rotatably fitted in said seat; a handle lever secured to said valve and provided with a stud; and a torsion spring located exteriorly of said case and having one

end thereof engaged with said projection, and the other arm with said stud. 40

2. In a gage cock, the combination, with a hollow case provided with an interiorly-located valve seat, and with an exteriorly-located arm formed with a pair of lateral pins; of a valve rotatably fitted in said seat; 45 a handle lever secured to said valve and provided with a stud; and a torsion spring located exteriorly of said case and formed with a coiled central portion embracing one of said pins, said spring having one end 50 thereof engaged with the other pin, and the other end with said stud.

3. In a gage cock, the combination, with a hollow case provided with an interiorly-located valve seat, and with a spout having 55 its bore opening directly through one wall of said seat; of a valve rotatably fitted in said seat and formed with steep spiral threads; a tubular member provided upon said case and formed with internal threads 60 co-acting with the first named threads, for causing a quick endwise movement of said valve when rotated; a handle lever secured to said valve; and an exteriorly-located torsion spring connected at one end with said 65 case, and at the other end to said lever, for normally holding said valve in closed position.

In testimony whereof I have hereunto set my hand in presence of two subscribing 70 witnesses.

EDWARD FRANCIS SHALLOW.
